PHOTOELECTRIC CONTROL OF VARIABLE-SPEED MECHANISM

William R. Perry, Columbus, Ind., assignor to
Reeves Pulley Company, Columbus, Ind., a corporation of Indiana

Original application March 28, 1932, Serial No.
601,606. Divided and this application April
22, 1937, Serial No. 138,344

10 Claims. (Cl. 271—2.3)

The present application is a division of my co-pending application Ser. No. 601,606, filed March 28, 1932, and relates to speed control mechanism, and more particularly to mechanism for controlling the speed of a driven element, such mechanism including light-sensitive means adapted to be dominated by a member associated with the driven element.

My invention may be embodied in many different forms, and I have herein illustrated several of them, but it is to be understood that I do not consider the specific form of any one of the mechanisms illustrated in the present application to be a limitation upon my invention. For instance, the specific control means of one illustrated embodiment of my invention might be applied to another illustrated embodiment without in any way violating the scope of my invention.

Essentially, the objects of the present invention are to control strand-forwarding mechanism in such a manner as to maintain a substantially constant time-weight ratio of the material being forwarded; attention being called to the fact that, in the present application, I shall use the term "strand" in a broad enough sense to include either a string-like element or a web or strip or the like, the cross section of which may be of any form, so long as the material is flexible in a direction perpendicular to the direction of movement of the material.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a diagrammatic isometric view of an embodiment of my invention;

Fig. 2 is a view of structure closely similar to that of Fig. 1, but showing cycling means associated with the control; and

Fig. 3 is a view of a similar mechanism associated with a different type of machinery to be controlled.

The structure of Fig. 1 is intended primarily for forwarding plastic material of very low tensile strength, in such a manner that the material will leave the mechanism under a substantially uniform weight-length ratio. The mechanism may be used, of course, for forwarding material of other characteristics, but its primary use is that above suggested.

The material 10 is led from a storage reel or other source between a pair of forwarding rolls 11 and 12, which may be the discharge rolls of a machine for making or treating the material, and the material may be of varying thickness and of varying width, whereby its weight per unit length is a variable. In the illustrated embodiment of my invention, the roll 11 is mounted upon a shaft 13 which carries a pulley 14 adapted to be driven, through the medium of a belt 15, by any suitable prime mover (not shown). The shaft 13 carries a second pulley 16 which, through the medium of a belt 17 drives a pulley 18 upon the in-put shaft 19 of a variable-speed transmission indicated generally at 20, and which is preferably but not necessarily of the well-known "Reeves" type. The transmission 20 is of well-known construction and need not here be described in detail. As usual, said transmission includes a screw shaft 21 for varying the speed ratio between the in-put shaft 19 and the out-put shaft 22. The screw shaft 21 carries a gear 23 with which meshes a pinion 24 on the spindle of a reversible electric motor 25.

The shaft 22 carries a pulley 26 which, through the medium of a belt 27, drives a pulley 28 upon a shaft 29, said shaft 29 carrying a forwarding roll 30 which cooperates with a roll 31 to forward the strand 10.

Since the material of the strand 10 is of very low tensile strength, it must necessarily be supported at intervals upon rolls such as the rolls 32 and 33. Two of said rolls, illustrated in Fig. 1, are spaced apart farther than others of the supporting series, whereby a portion 34 of the strand 10 is supported solely upon a floating idler roll 35 carried in a frame 36 depending from a rod 37. The upper end of said rod 37 is pivotally secured to one end 38 of a lever 39 suitably pivoted upon a base 40. The opposite end of said lever 39 carries an opaque counter-balancing block 41, said block and lever being so proportioned that, so long as the portion 34 of the strand 10 is of optimum weight-length ratio, the lever 39 will be maintained in a median position.

Adjacent the block 41 there is mounted a photo-electric cell 42, and a light source 43 is associated with said cell 42, but is positioned on the opposite side of the block 41, with respect to the cell 42. Said light source 43 is adapted to direct a beam 44 toward said cell 42. Spaced slightly beneath the cell 42 is a second photo-electric cell 45 with which is associated a light source 46 positioned immediately beneath the source 43, and adapted to direct a beam 47 toward

said cell 45. It will be obvious that, so long as the block 41 is maintained at a median position, the two cells 42 and 45 will be illuminated equally by the beams 44 and 47; but that any upward movement of the block 41 will decrease the intensity of the beam 44, and any downward movement thereof will decrease the intensity of the beam 47. It will also be obvious that a single light source capable of illuminating both of the cells 42 and 45 might be substituted for the two sources 43 and 46.

A source of electrical energy is indicated by the line wires 48 and 49. A wire 50 leads from the line 49 to the common terminal of the motor 25. A wire 51 leads from what may be termed the forward terminal of the motor 25 to one terminal 52 of a carbon-pile rheostat 53, the opposite terminal 54 of said rheostat being connected by the wire 55 to the line 48. What may be termed the reverse terminal of the motor 25 is connected by a wire 56 to one terminal 57 of a second carbon-pile rheostat 58, the opposite terminal 59 of which is likewise connected by the wire 55 to the line 48. It will be seen that, when the plunger 60 of the rheostat 53 is depressed, current will flow through the circuit 49, 50, 25, 51, 52, 53, 54, 55, 48 to cause forward rotation of the motor 25 which, in turn, will rotate the screw shaft 21 to increase the speed of the out-put shaft 22, and consequently to increase the speed of the roll 30. Conversely, when the plunger 61 of the rheostat 58 is depressed, current will flow in the circuit 49, 50, 25, 56, 57, 58, 59, 55, 48 to cause operation of motor 25 in the opposite direction to rotate the screw shaft 21 to decrease the speed of the shaft 22 and roll 30.

The primary coil 62 of a transformer is connected across the line wires 48 and 49 to excite the secondary coil 63 of said transformer. A wire 64 connects one end of said coil 63 to a wire 65 which is connected to the cathode of the photo-electric cell 42. A wire 66 connects the anode of said cell 42 with the grid 67 of the thermionic valve 68. The plate 69 of said valve is connected by a wire 70 with one end of a solenoid coil 71, the midpoint of said coil being connected by a wire 72 with the opposite end of the coil 63. The filament 73 of the valve 68 is energized through the medium of a wire 74 connected to an intermediate point on the coil 63 and to one side of the filament, and a wire 75 connected to the opposite side of said filament and to a wire 76 connected to the coil 63 at a point spaced somewhat from the point at which the wire 74 is connected to said coil 63.

A wire 77 connects said wire 64 with the cathode of the photo-electric cell 45, and the anode of said cell is connected by a wire 78 with the grid 79 of a second thermionic valve 80. The plate 81 of said valve 80 is connected by a wire 82 with the opposite end of the solenoid coil 71. The filament 83 of said valve 80 is connected to the wires 74 and 76 in parallel with the filament 73.

A wire 84 leads from a point 85 on the negative side of the transformer secondary 63 to impress upon the grids 67 and 79 of the thermionic valves 68 and 80, a negative potential, through resistors 86 and 87 shunted by condensers 88 and 89, respectively. When the cells 42 and 45 are fully illuminated, a further negative potential is impressed upon said grids 67 and 79 through said cells, respectively; and the device is so calibrated that the algebraic sum of the negative

potential impressed upon the grids through the wire 84 and the negative potential impressed thereon through the cells 42 and 45 is sufficient to prevent any current flow through the valves 68 and 80.

It will be seen that, so long as the block 41 is in its median position, neither end of the solenoid coil 71 will be energized, and the core 90 thereof will occupy a median position, as illustrated. If the intensity of the beam 44 is decreased, however, the value of the negative potential impressed upon the grid 67 will be arithmetically reduced, whereby current flow through the valve 68 and the upper portion of the solenoid coil 71 will be permitted and the core 90 will be moved upwardly to swing the arm 91 in a counter-clockwise direction to depress the plunger 60 of the rheostat 53, whereby the motor 25 will be energized to increase the speed of the shaft 22 and the roll 30. It will also be obvious that the speed of rotation of the motor 25 will be dependent upon the degree of movement of the core 90 which, in turn, is a function of the rate of current flow through the valve 68, that rate being dependent upon the degree of reduction in the intensity of the beam 44 falling upon the cell 42. Similarly, if the intensity of the beam 47 falling upon the cell 45 is reduced, the core 90 will be moved downwardly to depress the plunger 61 of the rheostat 58 to cause rotation of the motor 25 in the opposite direction at a speed dependent upon the degree of reduction of the intensity of the beam 47 falling upon the cell 45.

In the use of the mechanism disclosed in Fig. 1, the strand 10 is threaded in the manner illustrated. Normally, the parts will be in the positions illustrated, and the roll 30 will be rotated at a speed synchronous with the speed of the roll 11. If, as the strand 10 is forwarded, a portion of undue thickness reaches a position between the illustrated rolls 32 and 33, to be supported upon the roll 35, said roll 35 will be depressed with the result that the block 41 will be elevated to reduce the intensity with which the beam 44 illuminates the cell 42, whereby, in the manner above described, the arm 91 will be operated to depress the plunger 60. The motor 25 will thus be operated to increase the speed of the shaft 22 and roll 30. Since the roll 30 will then be operating at a speed greater than the speed of the roll 11, the material between said rolls 11 and 30 will be elongated, whereby the unduly thick portion will be reduced in thickness. Obviously, if the speed ratio between the rolls 11 and 30 is continued, the above-described attenuation will be carried beyond the desired point, whereupon the weight-length ratio of the portion 34 of web 10 will eventually be reduced below the optimum. When this occurs, the roll 35 will move upwardly beyond its median position, whereby the beam 47 will be intercepted and the motor 25 will be operated in the opposite direction to reduce the speed of the roll 30 to a value dependent upon the weight-length ratio of that portion of the strand currently supported upon the roll 35.

As above-described, this is, of course, a "hunting" control; and in Fig. 2 I have illustrated a modified embodiment of my invention whereby the hunting tendency of the control may be overcome.

The structure disclosed in Fig. 2 is identical with that disclosed in Fig. 1, except that the wire 92 has been substituted, in Fig. 2, for the wire 50 of Fig. 1, and a cycling mechanism has been

added to control the "hunting" tendency of the control.

The wire 92 leads from the line wire 49 to a contactor 93 carrying a contact button 94. Cooperatively associated with the contactor 93 is a second contactor 95 carrying a contact button 96 adapted to contact the button 94. Preferably, the contactor 95 is a spring finger, but it may be any one of a number of other suitable types. Said contactor 95 is connected by a wire 97 to the common terminal of the motor 25.

The shaft 13 carries a pulley 98 which drives, through the belt 99, a pulley 100 mounted upon a shaft 101, said shaft likewise carrying a pinion 102 meshing with a gear 103, said gear 103 driving a cam 104 associated with the projecting end of the contactor 95.

The parts of the organization are so proportioned and correlated that the cam 104 makes one complete revolution in the time which is required for a point on the web 10 to travel from a position between the rolls 11 and 12 to the supporting roll 33. The contact buttons 94 and 96 are normally separated, and are brought into contact only when the high portion of the cam 104 comes into engagement with the contactor 95, the shape of the cam being such that said buttons are in contact substantially during the time required for a point on the web to move from between the rolls 11 and 12 to a point on the roll 32; and being separated during the time required for said point to move thence to a point on the roll 33. It will thus be seen that operation of the motor 25 is possible only at intervals.

If, at a time when the contact buttons 94 and 96 are in contact, the portion 34 of the web 10 is unduly heavy, the motor 25 will be energized to increase the speed of the shaft 22, and consequently of the rolls 30 and 31. After a short period of operation, the motor circuit will be broken at 94-96, and the rolls 30 and 31 will continue to operate at increased speed during the time required for a point on the web 10 to move from the roll 32 to the support roll 33. At that time, the contacts 94 and 96 will again be closed, and the mechanism will "take another weight" of the material supported between rolls 32 and 33 to determine whether or not another adjustment of the variable speed transmission is required. If the portion 34 of the web 10 supported upon the roll 35 is now too light, the motor 25 will be operated in the reverse direction to reduce the speed of the rolls 30 and 31.

This arrangement cures the "hunting" defect of the organization of Fig. 1.

In Fig. 3 there is illustrated an embodiment of the present invention which is similar in some respects to that illustrated in Fig. 1, in that it comprises mechanism operable to deliver a given weight of material to a discharge station within a given period of time.

A first conveyor is indicated by the showing of a conveyor roll 105 about which passes one end of the conveyor belt 106. Said roll 105 is mounted upon a shaft 107 which carries a pulley 108 driven by a belt 109 from a pulley 110 on the output shaft 111 of a variable speed transmission indicated at 112. Said transmission includes a shifter shaft 113 carrying a gear 114 with which meshes the pinion 24 carried upon the spindle of the electric motor 25 identical with that disclosed in Fig. 1.

The input shaft 115 of the transmission 112 carries a pulley 116 driven by a belt 117 from a pulley 118 on a shaft 119, said shaft 119 carry-

ing a pulley 120 driven by a belt 121 from a prime mover (not shown), said shaft 119 likewise carries a roll 122 about which one end of a conveyor belt 123 is passed.

The elements 32 to 83, inclusive, 90, and 91, 5 of Fig. 3 are identical with the similarly indicated elements of Fig. 1, except that the wires 51 and 56 disclosed in Fig. 1 are reversed in Fig. 3, so that the wire 56 is connected to the forward terminal of the motor 25, while the wire 51 is 10 connected to the reverse terminal of said motor. Thus, it will be apparent that, in the organization disclosed in Fig. 3, if the roll 35 is depressed, the motor 25 will be operated to decrease the speed of the shafts 111 and 107. 15

A hopper 124 is associated with the conveyor belt 106 in a well known manner, so that material will be delivered from said hopper to said belt at a more or less constant rate which will be somewhat dependent upon the rate of movement of said belt 106. It will be assumed that containers are successively brought into registration with the discharge end of the conveyor belt 123. The object of the organization is, of course, to discharge a uniform weight of material into each of such containers. 20

Assuming that the belts 106 and 123 are moving at the same linear speed, and that material is being discharged from the hopper 124 onto the belt 106 at the desired rate, the roll 35 will 30 occupy the median position illustrated in which neither the beam 44 nor the beam 47 will be obstructed by the block 41. If, for some reason, an unduly large mass of material is deposited suddenly upon the belt 106 from the hopper 124, 35 that mass will shortly be deposited upon the belt 123, and will be carried onto that portion 125 of said belt 123 between the supporting rolls 32 and 33, and will there affect the roll 35. The roll 35 will thus be depressed, whereby the block 41 40 will be elevated, to intercept or decrease the intensity of the beam 44. Thereby, the motor 25 will be caused to rotate, shifting the transmission elements to reduce the speed of the shaft 107, thereby reducing the linear speed of the belt 45 106. As a result of this reduction, material will be less rapidly deposited upon the belt 123, whereby the time-weight ratio of the material carried across the roll 35 will be reduced and, after a suitable interval, said roll 35 will be lifted, where- 50 by the motor 25 will be operated in the opposite direction to bring the shafts 111 and 107 back to normal speed.

I claim as my invention:

1. Means for forwarding ductile material of 55 low tensile strength at constant weight per unit length, comprising forwarding means, means for driving said forwarding means, a forwarding roll spaced from said forwarding means, variable-speed means for driving said forwarding roll, a 60 vertically reciprocable idler roll positioned between said forwarding means and said forwarding roll, a portion of said material being constantly supported upon said idler roll, two vertically spaced photo-electric cells, a light source direct- 65 ing beams of light toward said cells, an opaque element shiftable in response to reciprocation of said idler roll, and normally disposed out of shielding relation with both of said cells and adapted, when shifted in either direction from its 70 normal position, to obstruct one or the other of said beams, and connections between said cells and said variable-speed means whereby, when said opaque element is shifted in response to downward movement of said idler roll, said vari- 75

able-speed means will be operated to increase the speed of said forwarding roll, and when said opaque element is shifted in response to upward movement of said idler roll, said variable-speed means will be operated to decrease the speed of said forwarding roll.

2. Means for forwarding ductile material of low tensile strength at constant weight per unit length, comprising a forwarding roll, means for driving said roll, a second forwarding roll spaced from said first roll, variable-speed means for driving said second forwarding roll, a vertically reciprocable idler roll positioned between said forwarding rolls, an opaque element urging upward movement of said idler roll, said material being supported at all times upon said forwarding rolls and upon said idler roll and the weight of such material supported upon said idler roll at an optimum length-weight ratio of material being just sufficient to counter-act the tendency of said last-mentioned means, two vertically spaced photo-electric cells, two light sources respectively directing beams of light toward said cells, said opaque element being shiftable in response to reciprocation of said idler roll, and normally disposed intermediate said beams and adapted, when shifted in either direction from its normal position, to obstruct one or the other of said beams, and connections between said cells and said variable-speed means whereby, when said opaque element is shifted in response to downward movement of said idler roll, said variable-speed means will be operated to increase the speed of said second forwarding roll, and when said opaque element is shifted in response to upward movement of said idler roll, said variable-speed means will be operated to decrease the speed of said second forwarding roll.

3. Means for forwarding ductile material of low tensile strength at constant weight per unit length, comprising forwarding means, means for driving said forwarding means, a forwarding roll spaced from said forwarding means, a variable-speed transmission connected to drive said forwarding roll at variable speeds, a reversible, variable speed electric motor dominating said transmission, a vertically reciprocable idler roll positioned between said forwarding means and said forwarding roll, a portion of said material being supported at all times upon said idler roll, two vertically spaced photo-electric cells, a light source directing beams of light toward said cells, an opaque element shiftable in response to reciprocation of said idler roll, and normally disposed out of shielding relation with both of said cells and adapted, when shifted in either direction from its normal position, to decrease the intensity of illumination of one or the other of said cells, and electrical connections including a pair of rheostats between said cells and said motor, whereby said motor will be energized to operate said transmission, upon movement of said opaque element from its median position, in a direction and at a speed dependent upon the direction and degree of movement of said opaque element from its median position.

4. Means for forwarding material in accordance with a predetermined time-weight ratio, comprising a weighing station, means for continuously delivering material to supported relation at said weighing station, means for continuously withdrawing material from said weighing station, mechanism for driving said delivering and withdrawing means, said mechanism being adjustable to vary the speed of operation of one

of said means with respect to the speed of operation of the other of said means, light-sensitive means connected to control said mechanism, movable means at said weighing station movable in response to the weight of material continuously delivered thereto, and means operated by said movable means and controlling said light-sensitive means.

5. Means for forwarding material in accordance with a predetermined time-weight ratio, comprising means for continuously delivering material to a weighing station, means for continuously withdrawing material from said weighing station, mechanism for driving one of said means, variable-speed mechanism for driving the other of said means at speeds variable with respect to the speed of said one means, means for varying the output speed of said variable-speed mechanism including a light-sensitive cell, a light source directing a light beam toward said cell and means for varying the intensity of said beam falling upon said cell, and movable means at said weighing station movable in response to the weight of material delivered thereto, said movable means dominating said light-intensity-varying means.

6. Means for forwarding material in accordance with a predetermined time-weight ratio, comprising means for continuously delivering material to a weighing station, means for continuously withdrawing material from said station, a prime mover connected to drive one of said means directly and to drive the input shaft of a variable-speed transmission, means connecting the output shaft of said transmission to drive the other of said means, an electric motor for varying the speed ratio between said input and output shafts, means including a light-sensitive cell, a light source directing a light beam toward said cell, and beam-obstructing means, for controlling said motor, and movable means at said weighing station movable in response to the weight of material delivered thereto, said movable means dominating said beam-obstructing means.

7. Means for forwarding material in accordance with a predetermined time-weight ratio, comprising means for continuously delivering material to a weighing station, means for continuously withdrawing material from said station, constant-speed mechanism for driving said delivering means, variable-speed mechanism for driving said withdrawing means, electrically operated means for controlling the output speed of said variable-speed mechanism, means including a light-sensitive cell, a light source directing a light beam toward said cell, and beam-obstructing means, for controlling said motor, and movable means at said weighing station movable in response to the weight of material delivered thereto, said movable means dominating said beam-obstructing means.

8. Means for forwarding material in accordance with a predetermined time-weight ratio, comprising means for continuously delivering material to a weighing station, means for continuously withdrawing material from said station, variable-speed mechanism for driving said delivering means, constant-speed mechanism for driving said withdrawing means, electrically operated means for controlling the output speed of said variable-speed mechanism, means including a light-sensitive cell, a light source directing a light beam toward said cell, and beam-obstructing means, for controlling said motor, and movable means at said weighing station

movable in response to the weight of material delivered thereto, said movable means dominating said beam-obstructing means.

9. In combination, means for advancing a strand, a pair of spaced stationary elements providing supports for portions of said strand, a movable element intermediate said stationary elements, supporting at all times the portion of said strand between said stationary elements and movable in response to weight changes impressed thereon, variable-speed mechanism for driving said advancing means, means associated with said movable element and with said variable-speed mechanism for controlling the output speed of said variable-speed means in accordance with the position of said movable element, and cycling means normally rendering said last-mentioned means ineffective and operable to render said last-mentioned means effective only at intervals corresponding substantially to the time required for a given point on said strand to move from one of said stationary elements to the other of said stationary elements.
10. The combination with a variable-speed driving mechanism, of means for controlling the driving speed thereof comprising means for advancing a strand, a pair of spaced stationary elements providing supports for portions of said strand, a movable element intermediate said stationary elements, supporting at all times the portion of said strand between said stationary elements and movable in response to weight changes impressed thereon, means associated with said movable element and with said variable-speed mechanism for controlling the speed of said variable-speed means in accordance with the position of said movable element, and cycling means normally rendering said last-mentioned means ineffective and operable to render said last-mentioned means effective only at intervals corresponding substantially to the time required for a given point on said strand to move from one of said stationary elements to the other of said stationary elements.

10. The combination with a variable-speed driving mechanism, of means for controlling the driving speed thereof comprising means for advancing a strand, a pair of spaced stationary elements providing supports for portions of said strand, a movable element intermediate said stationary elements, supporting at all times the portion of said strand between said stationary elements and movable in response to weight changes impressed thereon, means associated with said movable element and with said variable-speed mechanism for controlling the speed of said variable-speed means in accordance with the position of said movable element, and cycling means normally rendering said last-mentioned means ineffective and operable to render said last-mentioned means effective only at intervals corresponding substantially to the time required for a given point on said strand to move from one of said stationary elements to the other of said stationary elements.

WILLIAM R. PERRY.
